UNITED STATES PATENT OFFICE.

JOHN W. CORDINGLEY, OF METHUEN, MASSACHUSETTS, ASSIGNOR OF ONE-HALF TO
WILLIAM CORDINGLEY, OF METHUEN, MASSACHUSETTS.

CURTAIN-POLE SUPPORT.

1,140,255.

Specification of Letters Patent. Patented May 18, 1915.

Application filed November 6, 1913. Serial No. 799,563.

To all whom it may concern:

Be it known that I, JOHN W. CORDINGLEY, a citizen of the United States, residing at Methuen, in the county of Essex and State 5 of Massachusetts, have invented certain new and useful Improvements in Curtain-Pole Supports, of which the following is a specification.

This invention relates to an improved curtain support and the principal object of the 10 invention is to provide a device which is so constructed that the pole engaging brackets may be adjustably connected with supporting plates and securely held in the adjusted 15 position.

Another object of the invention is to so construct the plate that the bracket which is connected with the same will be securely held in place and prevented from having 20 longitudinal movement upon the plate after being put in an adjusted position.

Another object of the invention is to so construct the device that the plate and bracket can be formed of sheet metal and 25 the plate bent to assume the desired shape.

Another object of the invention is to so construct the plate that vertical movement of the bracket is prevented thereby doing away with any danger of the bracket being 30 disengaged from the plate when operating the curtain.

This invention is illustrated in the accompanying drawings, wherein;—

Figure 1 is a front elevation of a bracket 35 and plate with the curtain in place; Fig. 2 is a sectional view along the line 2—2 of Fig. 3 is a side elevation of the bracket removed from the plate.

The supporting plate 10 which forms part 40 of this invention is bent longitudinally to form the upper and lower flanges 11 and 12, the lower flange extending at substantially right angles to the central portion of the plate and the upper flange extending from 45 the central portion at an angle of substantially 45°. The end portions of the plate are provided with openings so that securing devices, such as screws 13 may be passed through the plate to securely connect the 50 plate with a window frame.

The lower flange 12 is provided with a plurality of slots forming fingers 14 which extend the full depth of the flange as shown in Fig. 2 and the upper flange is provided 55 with short slots forming short fingers 15.

The fingers 15 are formed short so that the inner portion of the upper flange will provide means for supporting the bracket 16, and prevent the bracket from dropping through the fingers 14 after being put in 60 place. This bracket 16 is provided with an elongated upper portion 17 which is of substantially the same width throughout its length and is provided with a diagonally extending slot 18 which extends at the same 65 angle as the flange 11. The lower end portion 16 of the bracket extends at an angle to the upper end portion and is provided at its outer end with a head 19 in which there is formed a slot 20 for the reception of the 70 pivot pin 21 carried by the curtain roller 22. It is of course obvious, that the bracket at the opposite side of the curtain will be provided with a round opening instead of with an elongated slot.

The operation of this device is as follows:—The plates are first secured to the window frame upon opposite sides and the brackets are then connected with the plates so that they will be the proper distance 80 apart to accommodate the curtain. When the brackets are connected with the plates, the fingers 14 extend upon opposite sides of the brackets and the upper flanges 11 extend into the slots 18 with the upper portion of the brackets positioned between the 85 fingers 15. The fingers 14 and 15 prevent the brackets from moving longitudinally upon the plates and the upper flanges 11 prevent the brackets from moving vertically and slipping out of engagement with the plates so that they can drop down through the fingers 14. It will thus be seen that the brackets will be removably but very securely connected with the plates and 90 that the brackets can be easily adjusted in case it is desired to put up a longer or a shorter window curtain.

What is claimed is:—

1. A curtain support comprising a plate 100 having its side portions cut to form fingers, said plate being bent longitudinally to form upper and lower flanges, the lower flange extending at substantially right angles to the central portion of the plate and the upper flange extending at substantially an angle of forty five degrees, and a bracket fitting between the fingers of said upper and lower flanges and provided with a slot to receive said upper flange whereby when 110

said bracket is connected with said plate, said bracket will be prevented from having longitudinally and transverse movement upon said plate.

- 5 2. A curtain support of the character described comprising an attaching plate provided with upper and lower flanges, said flanges being provided with slots forming fingers, the fingers of said lower flange extending the full depth of the flange and the fingers of the upper flange being relatively short to leave the inner portion of the upper flange unbroken, a curtain pole supporting means fitting between the fingers of said two flanges and provided with a slot in which the unbroken inner portion of said upper flange fits.
- 10 3. A curtain support of the character described comprising supporting means provided with upper and lower flanges having relatively long and short fingers, and curtain pole supporting means fitting between said fingers and having its upper end portion provided with a slot to receive said upper flange.
- 15 4. A curtain support of the character described, comprising supporting means provided with upper and lower fingers, and curtain pole supporting means fitting be-

tween said fingers and engaging the upper 30 portion of said supporting means.

5. A curtain support of the character described comprising supporting means provided with upper and lower flanges, curtain pole supporting means removably connected 35 with said upper flange, said flanges being provided with means for engaging opposite side portions of said curtain pole supporting means to prevent longitudinal movement of said curtain pole supporting means 40 upon said first mentioned supporting means.

6. A curtain support of the character described comprising supporting means, curtain pole supporting means removably connected with said first mentioned supporting 45 means, and means extending from the upper and lower portions of said first mentioned supporting means for engaging said curtain pole supporting means to prevent longitudinal movement of the same upon said first 50 mentioned supporting means.

In testimony whereof I affix my signature in presence of two witnesses.

JOHN W. CORDINGLEY.
